MEANS OF MOUNTING BUTTONS AND
SIMILAR ARTICLES

Samuel Eppy, Jamaica, N. Y.

Application July 8, 1943, Serial No. 493,942

4 Claims. (Cl. 218—18)

The present invention relates to a means of mounting buttons and articles of a similar nature, which embody a body-portion and an axially projecting attaching shank, on cards or other devices, for purposes of display and to facilitate distribution.

In my co-pending application for Letters Patent, Serial No. 456,447 filed August 26, 1942, for "Method and means of mounting buttons and similar articles," of which this application is a continuation in part, I have pointed out these shortcomings, economically and otherwise, of prior conventional methods employed in fastening buttons of the shank type to cards and the like, the shanks either being entered through the cards for frictional engagement therewith, or sewn thereto by a continuous thread, looped through the eye of the shank, with the shank disposed on the face of the card or extending therethrough with the stitching along the back of the card. All of these methods involve a plurality of hand operations and do not afford the required security against accidental separation of the buttons from the cards in handling, as frequently results from the breaking of a thread or the distortion of the apertures in the card in which the button shank is frictionally entered for retention.

The present invention is directed to the same important objectives as that of my aforesaid co-pending application, the primary object of this invention being to provide a simple and efficient means of rapidly affixing buttons to cards and other supporting elements of the kind, in a manner that will insure against accidental separation of the button from the card; each of a series of buttons grouped on a card being individually fastened thereto, so that, if desired, one or more buttons may be removed, without impairing the security of the fastening of the remainder. Obviously, this is not feasible, where continuous or so-called chain stitching is employed to affix buttons to cards.

A further important object of this invention is to provide for fastening buttons of the shank type to the usual imperforate card, or other suitable supporting element, by mechanically introducing a wire staple through the card and the eye of a shank of a button supported above the card and clinching the free ends of the staple about the shank to swivelly connect the button to the card.

Another important object of this invention is to provide a simple and efficient improvement in the mechanism of a standard wire stitching ma-

chine, for attaining the aforementioned objectives in a practical and economical manner; my improvements being readily incorporated in new constructions, and being of a nature to permit of their application to existing machines, to effect their conversion at relatively small expense, to gain the aforesaid attendant advantages of increased production and lower manufacturing costs.

10 Other objects and advantages flowing from the practicing of my invention will become manifest as the description proceeds.

In the accompanying drawings, I have shown certain preferred embodiments of the button fastening means which may be employed either in new constructions or in the conversion of existing wire stitchers for the practicing of my invention. Changes in details of the means shown to meet different production and operating requirements, it is understood, may be made, within the spirit and scope of this disclosure.

In the drawings:

Figure 1 is a fragmentary elevation of a wire stitching or staple-forming machine, embodying improvements for attaching buttons to cards, in accordance with my invention.

Figure 2 is a fragmentary elevation of the wire-forming mechanism of the machine showing the 15 position of the associated elements thereof at one stage of movement.

Figure 3 is a fragmentary end elevation of the 20 associated elements of Figure 2.

Figure 4 is a fragmentary elevation of the wire-forming mechanism of the machine showing the 25 position of the associated elements thereof at another stage of movement but with certain elements shown in Fig. 2 removed.

Figure 5 is a fragmentary end elevation of the 30 associated elements of Figure 4.

Figure 6 is an enlarged view of a part of the 35 mechanism of Figure 1, showing the position of the clincher bar relative to the bender bar, when the button is applied to the clincher bar.

Figure 7 is a view similar to Figure 6, showing the clincher bar in its lowermost or staple-clinching position, in which operation the button and card are interconnected.

Figure 8 is another view of the elements shown 40 in Figure 6, illustrating the position of the clincher bar at the limit of its upward travel and the card, with button attached, in the position in which it is removed from the machine table.

Figure 9 is a view corresponding to Figure 6,

showing a modified form of clincher bar and a cooperating recessed bender bar; and

Figure 10 is an enlarged view of a part of a still further modified form of clincher bar.

Referring now to the drawings in detail, in which like characters of reference are employed to designate similar parts in the several views, in carrying my invention into effect, I use a conventional imperforate button card, to which the buttons are swivelly attached by individual wire staples, in the operation of a standard type wire stitcher or stapling machine embodying my improvements. Since the construction and mode of operation of this machine are well known in the art, only so much of the mechanism thereof as is essential to a clear understanding of the nature of my improvements and the manner in which they function, in the operation of the machine, will be described in detail.

In the wire stitcher or stapling machine shown, the wire W is introduced to the mechanism through a suitable guideway and fed by and between gripping elements 10a and 10b to staple-forming position by a mechanism generally indicated at 11, actuatable by the feed slide 12. At the staple-forming position, the wire W is severed by the cooperation of a cutting edge 13 on the bender bar A with the cutting edge 14 on anvil block B. The anvil block pivotally supports, as on projecting stud 15, an anvil C which incorporates a transversely extending guideway 16, through which the free end of the wire is fed prior to the severing step and in which the wire is held in position for staple formation in conjunction with the head 17 of the pivoted lever D, which anvil C and lever D are maintained in such cooperative wire-holding position by leaf springs 18 and 19 respectively.

The thus supported severed wire is subsequently bent into U-shaped staple conformation U by the movement of the bender bar A in the direction of the arrow of Figure 2, as the bender bar is moved upwardly by pressure slide E progressively from its position in Figure 2 to that shown in Figure 3. In the upward movement of the bender bar, the driver bar F, carried in the guideway 20 of the bender bar, travels with the bender bar as the latter is displaced by the pressure slide. As the driver bar is thus displaced with the bender bar, an outer cam conformation, adjacent the head 21, contacts with and displaces the anvil C outwardly against the pressure of the anvil spring 19, until contact is made by the forwardly extending head 21 with the base of the formed staple.

In the meantime, the bender bar has reached the extreme limit of its upward movement at the level of the table T and the formed staple U is maintained in position by the cooperation of the head 21 of the driver bar resting against the base of the staple, while the head 17 of the pivoted lever D rests between the legs of the staple. At this time, the toggles 22a and 22b, respectively pivotally connected to the pressure slide E and the end of the driver bar, are displaced to a position so that the stub shaft 22c, connecting the toggles, is guided along the cam surface 22d of the toggle guide piece G, thereby displacing the driver bar F in an upward movement relative to the bender bar and against the base of the staple, until the staple is pushed substantially to the level of the table T. As the driver bar F moves upwardly, the inner surface thereof presses against the head 17 of the pivoted lever D, to urge the lever rearwardly against its spring 18,

thus displacing the head out of holding position with respect to the legs of the staple. At this stage, the staple is now held in position for the cooperative action of the clincher bar, as will be later described.

The functioning of the wire-feeding mechanism, the staple-forming means and the staple-clamping means occurs in the usual timed relation; the clincher bar K, fixed to the clincher post 10 23, by the clamp 24, being actuated progressively in relation to the actuation of the bender bar, by the oscillation of the clincher arm (not shown) in response to the operation of the conventional treadle.

15 For practicing my invention, in lieu of the customary clincher bar, I employ a clincher bar K recessed between the head and attaching ends thereof, to provide for clearance of the head of a button by the clincher bar, when the button is supported relative thereto, to dispose its shank 20 for fastening to a card positioned beneath the clincher bar. In this fastening or staple-clamping operation, one leg of the staple is projected through the eye or aperture of the shank and bent in the opposite directional movement of the coacting leg of the clincher bar through the shank aperture, the other leg of the staple being shaped and the clinching of the opposite legs being effected externally of the shank, as will 25 become evident.

As herein shown, the clincher bar embodies the usual attaching end, indicated at 25, engageable by the aforesaid clamp 24 for fixing it to the post 23 for movement therewith. Preferably integral 30 with the attaching end 25 of the clincher bar, is a laterally offset, vertically dependent arm 26, terminating in a horizontal inwardly disposed extension 27, forming the head or die end of the clincher bar, in which the staple-shaping and 35 clamping surfaces are embodied, as hereinafter explained, the resulting disposition of the head in vertically spaced relation to the attaching end 25 of the clincher bar, affording ample clearance for the performance of the button fastening operation, in the manner hereinafter described.

The die or staple-shaping and clinching surfaces incorporated in the head 27 include the usual laterally spaced surfaces conformed to engage the opposite legs of a staple projected to clinching position in the upward travel of the bender bar A and a connecting web portion 28 for oppositely bending the free ends of the staple legs in the completion of the clinching operation. However, in lieu of the customary laterally spaced 45 guide surfaces, both parallel to the longitudinal axis of the clincher bar, only one of these surfaces, as indicated at 29, is vertically disposed, the opposite coacting staple-engaging surface, being formed in an angularly offset dependent finger 30, the diameter or cross-sectional area of which will admit of its passage through the eye or aperture of the shank of a button for coacting engagement with a staple projected therethrough. As will be noted, the head-forming extension 21 is of the appropriate configuration and dimensions to provide for the embodiment of the staple-guiding and clinching surfaces therein, with the center line of the web portion 28 in alignment with the vertical axis of the clincher bar for the 50 cooperation of the clincher and the staple-engaging surfaces thereof with the bender bar and the projected staple in the usual manner.

In the performance of a button stapling or fastening operation, a card of the appropriate size and shape, indicated at 31, is superimposed upon

the table T, beneath the clincher bar K. The button, indicated at S, is held supported adjacent the clincher bar K, with a portion of the head disposed within the recessed area of the clincher bar and the finger 30 of said bar entered in the eye or aperture 32 of the shank 33 of the button, as shown in Figure 6. As the clincher bar descends, in response to the actuation of the operating treadle, the button maintained in engagement with the finger 30 descends with it to clinching position, one of the legs of the staple, indicated at 34, projected through the card 31, in the upward movement of the bender bar A, entering the eye of the shank for engagement by the guide surface of said inclined finger 30. The other leg of the staple is engaged outwardly of the end of the shank by the coacting surface 29 of the clincher bar head, the shank, as will be obvious, being straddled, between the aperture and the end thereof, by the legs of the staple as it is projected in one direction and the oppositely moving guide and forming surfaces of the clincher bar, the fastening operation being completed as the ends of the staple legs are oppositely bent in clinching position, by engagement with the web portion 28 of the clincher bar. (See Figure 7.)

As the clincher bar recedes, in its upward stroke, the shank of the button is dislocated from engagement with the finger 30 of the bar and the card drawn outwardly from beneath the clincher bar, in the direction of the arrow in Figure 8.

In the form of the invention shown in Figure 9, the top of the bender bar A is undercut or recessed, as at A', to provide for operation of the clincher bar with oversize buttons, as at S', that is, buttons in which the radius from the shank to the peripheral edge of the head is such that in the descent of the clincher bar to clinching position, the head of the button will be urged into engagement with the face of the card. Under the pressure of the abutting button, the card 31 is deformable, as at 31a, within the area of the recess A' of the bender bar, as clearly shown in Figure 9, so as to maintain the relative positions of the shank aperture and the coacting staple leg and clincher bar finger 30, for the completion of the clinching operation in the manner described with respect to the structure of Figures 1 to 8, inclusive, it being manifest that the clincher bar of Figure 9 corresponds structurally and in its mode of operation to that of the preceding figures.

Referring to Figure 10, a still further modification of the clincher bar is disclosed, wherein the button S may be held in substantially horizontal position. The attaching end 35 of the clincher bar K incorporates a vertically dependent arm 36, terminating in a horizontal inwardly disposed extension 37, forming the head or die end of the clincher bar in which the staple-shaping and clamping surfaces are embodied. At the free end of the extension 37, there is formed a slightly arcuate but substantially horizontally disposed finger 38 having a U-shaped cross-section sufficient to admit the passage of the free ends of the staple at its opposite ends 38a and 38b; the finger being of such thickness as to admit of its passage through the eye or aperture of the shank of a button S, which is thus supported in substantially horizontal position.

Obviously, the recessed bender bar may be equally advantageously used in the performance of stapling operations with buttons of smaller

diameter than that herein shown, in the manner of the embodiment of the invention of Figures 1 to 8, inclusive, the recessing of the upper end of the bender bar increasing the utility of a given machine or mechanism by increasing the number of sizes of buttons which may be fastened to cards in the operation thereof.

Where a plurality of buttons are to be grouped upon a card, as each button is fastened in its proper position, and the button released from the clincher bar, the card is shifted beneath the bar to provide a new button position, another button being then supported in engagement with the clincher bar for the succeeding fastening operation, the operations being repeated until all of the buttons of the group have been stapled to the card.

While I have described my invention as it may be carried into effect with a particular type of wire stitcher, as herein shown, it will be evident that the means I employ for connecting the buttons to the cards may be employed to equal advantage in the operation of other forms of wire stapling machines, or may be incorporated in machines especially designed for the embodiment of my invention therein; also that the clincher bar may be recessed to provide the necessary button clearance in other ways to meet production and operational requirements, within the spirit and scope of this disclosure.

I claim:

1. In a mechanism for stapling a button having an eyed shank to a card comprising means for vertically moving a staple to project the legs thereof through the card, a vertically movable clincher member embodying a downwardly extending arm laterally offset relative to the vertical axis of the clincher member and an element projecting laterally of said arm to define with this latter a recess intersected by said vertical axis of the clincher member, said element being undercut at the free end thereof to form a terminal finger adapted to be entered into the eye of the shank of a button having its head extending into said recess, said undercut end of the element embodying die surfaces adapted to turn and oppositely guide the legs of the staple toward one another into juxtaposition, and means for actuating said clincher member and said staple moving means toward one another.

2. In a mechanism for stapling a button having an eyed shank to a card comprising means for vertically moving a staple to project the legs thereof through the card, a vertically movable clincher member having its lower end shaped to define a recess therein and a terminal laterally projecting element, said element being undercut at the free end thereof to form a finger adapted to be entered into the eye of the shank of a button having its head extending into said recess, said undercut end of the element embodying die surfaces adapted to turn and oppositely guide the legs of the staple toward one another into juxtaposition, and means for actuating said clincher member and said staple moving means toward one another.

3. In a mechanism for stapling a button having an eyed shank to a card comprising means for vertically moving a staple to project the legs thereof through the card, a vertically movable clincher member having its lower end shaped to define a recess intersected by the vertical axis of the clincher member and a terminal substantially horizontal laterally projecting element, said element being undercut at the free end thereof to

form a finger adapted to be entered into the eye of the shank of a button having its head extending into said recess, said undercut end of the element embodying die surfaces adapted to turn and oppositely guide the legs of the staple toward one another into juxtaposition, and means for actuating said clincher member and said staple moving means toward one another.

4. In a mechanism for stapling a button having an eyed shank to a card comprising means for vertically moving a staple to project the legs thereof through the card, a vertically movable clincher member embodying a downwardly extending arm laterally offset relative to the vertical arm of the clincher member and an element

projecting laterally of said arm to define with this latter a recess intersected by said vertical axis of the clincher member, said element being undercut at the free end thereof to form a downwardly projecting terminal finger angularly offset relative to the vertical axis of the clincher member adapted to be entered into the eye of the shank of a button having its head extending into said recess, said undercut end of the element embodying die surfaces adapted to turn and oppositely guide the legs of the staple toward one another into juxtaposition, and means for actuating said clincher member and said staple moving means toward one another.

SAMUEL EPPY.
